IGNITION MAGNETO

Umberto Quintavalle, Milan, Italy, assignor to
 Fabbrica Italiana Magneti Marelli Soc. An.,
 Milan, Italy, a corporation of Italy

Application September 25, 1936, Serial No. 102,606
 In Italy October 4, 1935

4 Claims. (Cl. 171—209)

This invention relates to the formation of the parts of the magnetic circuit or path in magneto-electric ignition devices in which pole members are embedded in a cast body, and said pole members form pole shoes and arms extending from said pole shoes having a reduced thickness with respect to said pole shoes.

The present invention includes the provision of a magnetic circuit or path by locating a stack 10 of superimposed iron sheets or laminations for each pole of said circuit in the mould where the body of the apparatus is cast and then the excess portions of said sheets or laminations are subsequently trimmed off by machining.

15 Each stack intended to form a pole piece has arms extending therefrom, preferably comprising sheets. Each sheet includes a portion intended to form the pole shoe and, on one side thereof, a tongue having a width smaller than 20 the length of the pole shoe. The adjacent sheets of the stack have their tongues staggered or offset with respect to one another to form in 25 their entirety an arm having a reduced thickness and a side surface of suitable extent for the connection of said arm with other parts of 30 the magnetic circuit.

The above outlined arrangement is of advantage when said arms are to be connected with the ends of the core of a winding located intermediate them, because the reduced thickness of 35 said arms secures a maximum space available for said winding within a given overall size of the whole, and a proper area for the surface on which said core and arms contact with each other. A 40 further advantage is secured by the fact that all the sets of sheets of the pole members are in direct contact with the winding core.

On the annexed drawing an embodiment of this invention is illustrated by way of example, 45 and

Figure 1 is a fragmentary longitudinal section of a portion of the body of a magneto electric ignition apparatus with parts removed on section line 1—1 of Fig. 2;

45 Figure 2 is a transverse section on line 2—2 of Fig. 1;

Figure 3 is a separate perspective view of a stack of iron sheets or laminations forming a pole piece which has a pole shoe and an arm;

50 Figure 4 shows separately one of the sheets forming the stack shown in Figure 3, on a reduced scale;

Figure 5 shows separately another one of the sheets forming the stack shown in Figure 3, on a reduced scale;

Figure 6 is a diagrammatic transverse section of the arm of a pole member as obtained after the sheets forming said pole member have been superimposed, and

Figure 7 is a similar section after said stack 5 has been subjected to an operation to reduce the thickness of the arm of the pole member.

In the illustrated construction the magnetic circuit which is assumed to belong to an ignition magneto for internal combustion engines and in 10 which the parts of said magneto which are not directly involved in the present invention are omitted, includes four pole faces 10, 10', 20, 20' provided by two pairs of pole members 1, 2 and 1', 2' located in front of each other in pairs and 15 a core 8 having a winding 9 thereon and connected with said pole members as hereinafter described. The pole members are engaged in the requisite respective position in the body 3 by causing them to be embedded in the mass of 20 non-magnetic metal forming said body 3 at the time of casting.

For such a purpose the stacks of sheets forming the several pole members are located in the mould intended for casting said body 3 without 25 interconnecting them and then metal is poured in said mould to form said body 3 and embed said sheet stacks therein.

Each of the pole members 1, 1' comprises 30 superimposed iron sheets or laminations (Fig. 3) forming a stack and may be interconnected by means of bolts, screws, rivets or in any preferred manner. The sheets or laminations include each a portion 1a which extends in a direction parallel to the axis of the space for the magneto rotor 35 intermediate said pole shoes, as well as portions 1b, 1c as hereinafter described, forming in their whole a side arm 5 or 5', in respect of pole member 1 or 1' respectively, intended to provide a portion of the magnetic circuit or path. 40

To form the arms 5, 5' each sheet of the pole members 1, 1' includes a narrow tongue, as 1b or 1c, extending from said portion 1a. Each of the arms is thus connected with the respective pole shoe only along a portion of the longitudinal 45 extent of the same.

In order that the arms 5, 5' of the pole members 1, 1' may have each a reduced thickness with respect to the associate pole shoe 1, two sets of sheets are used to form each pole member. The 50 sheets all have a general L-shape but a respective different configuration. The sheets are shown separately and referenced by 6 and 7 each in its whole in Figs. 4 and 5 where the portions 1a thereof providing a pole shoe as 1 are shown and 55

1b, 1c are the tongues intended to form an arm as 5. Such tongues extend transversely from the respective portions 1a and have a restricted size in the direction in which the length of portions 1a extends. Further, said tongues 1b, 1c have a staggered or offset position along the extent of portions 1a of the respective sheets. The portions 1a are identical in all the sheets of both sets and sheets of different sets. In other words sheets 10 of the type of Figures 4 and 5 respectively, alternate in each stack to cause said tongues 1b, 1c to be adjacent to each other but staggered or offset in the direction of the thickness of the arm 5 or 5', as shown in Figure 6.

15 Thus in each stack the portion thereof forming an arm as 5 or 5' has a width, that is a size in the direction in which pole shoe portions 1a extend, which is the sum of the widths of tongues 1b, 1c while the actual or total thickness of iron 20 laminations or sheets in each arm is one half of the thickness of pole shoe 1 that is of the thickness pertaining to the number of sheets forming the stack and pole shoe 1.

The thickness of the arm 5, 5' of each pole 25 member may thus be made smaller than the thickness of the pole shoe 1 by compressing or collapsing said stack in the region thereof forming said arm. Such operation may be carried out by bending tongues 1b, 1c where they connect with portions 1a of the respective sheets to impart to the pole members the shape shown in Figures 2 and 3 where the tongues 1b, 1c of each set approach each other and form a coherent piece 5 or 5' whose thickness (as shown 30 in Figure 7) is one half of the initial one (Figure 6).

On the other hand by imparting a proper width to tongues 1b, 1c in the direction of the longitudinal extent of the portions 1a of the respective sheets, the requisite width may be imparted 40 to the faces of the arms 5, 5' and both sets of sheets 1a, 1b and 1a, 1c partake directly in the formation of said arms.

Thus the overall size and weight of the magnetic circuit are reduced and the operative conditions of said circuit are improved, particularly when all the sheets of the pole member are required to connect directly with another member of the magnetic circuit as a core 8 of a winding 9. 45 The pole members 2 and 2' consist each of a stack of iron sheets and they are interconnected with respective pole members 1 and 1' by suitable 50 cross bridges 4, 4'.

The sheets 1a, 1b and 1a, 1c may have a dif-

ferent configuration with respect to the illustrated ones and more particularly their tongues 1b, 1c may have a non-rectilinear configuration and/or extend at an angle different from a right angle with respect to the respective portion pertaining to the pole shoe 1. 5

Further, a larger number of sets of sheets as 6, 7 than two may be used with the sheets of the several sets having then such a configuration of the tongues as 1b, 1c that the sheets of several 10 types are staggered or offset longitudinally of the respective pole shoes after they have been piled up in a stack.

What I claim as my invention and desire to 15 secure by U. S. Letters Patent is:

1. In an ignition magneto a pole member comprising a stack of sheets each having a portion to form a pole shoe and a tongue, said sheets being superimposed with said pole shoe portions adjacent one another and said tongues offset from 20 one another in adjacent sheets, said tongues being bent into contact with one another to form a pole arm having a reduced thickness with respect to said pole shoe.

2. In an ignition magneto, a pole member comprising a stack of sheets each having a portion to form a pole shoe and a portion to form a tongue, said sheets being superimposed with said pole shoe portions adjacent one another and said tongues being offset from one another in adjacent sheets, said tongues being deformed to provide a pole arm of less thickness than said pole shoe. 25

3. In an ignition magneto, a pole member comprising a stack of sheets each including a portion substantially equal in all said sheets to form a pole shoe and a tongue to form a pole arm, said sheets being superimposed with said pole shoe portions together and said tongues offset from one another in adjacent sheets, said tongues being 35 bent in contact with each other to provide a pole arm having a reduced thickness with respect to said pole shoe.

4. In an ignition magneto a pole member comprising a stack of sheets each including a portion to form a pole shoe and a tongue, said sheets being superimposed with said pole shoe portions coincident and said tongues offset from one another in alternate sheets, the superimposed 45 tongues being bent in contact with each other to form a pole arm having a reduced thickness with respect to said pole shoe. 50

UMBERTO QUINTAVALLE.
